DESIGN FOR A COMBINED TRAY AND CONDIMENT DISPENSING UNIT

Gabriele Toni Schreiber, known as Gaby Schreiber, London, England, assignor to Runcolite Limited, London, England, a company of Great Britain

Application May 25, 1948, Serial No. 146,601

Term of patent 7 years

(Cl. D44—22)

To all whom it may concern:

Be it known that I, Gaby Schreiber, subject of the King of Great Britain and Ireland, residing at London, England, have invented a new, original, and ornamental Design for a Combined Tray and Condiment Dispensing Unit, of which the following is a specification, reference being had to the accompanying drawing, forming part thereof.

Fig. 1 is a perspective view of a combined tray and condiment dispensing unit, showing my new design;

Fig. 2 is another perspective view showing the opposite side; and

Fig. 3 is an inverted plan view thereof.

I claim:

The ornamental design for a combined tray and condiment dispensing unit, as shown.

GABRIELE TONI SCHREIBER,
Known as Gaby Schreiber.
